UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

TERRY-LOOM.

1,322,730.

Specification of Letters Patent. Patented Nov. 25, 1919.

Application filed September 16, 1918. Serial No. 254,326.

To all whom it may concern:

Be it known that I, ALONZO E. RHOADES, of Hopedale, in the county of Worcester and State of Massachusetts, have invented certain new and useful Improvements in Terry-
5 Looms, of which the following is a specification.

In terry looms of the character that weave towels (commonly known as "Turkish") it 10 is customary to have such an organization that alternating stripes of plain fabric and of pile fabric can be woven at both ends of the pile body. The present improvements consist in a pattern mechanism determining 15 such weaving. The pattern mechanism controls the beat-up motion, the let-off and the let-back.

The terry or pile weave in such looms has 20 customarily been effected by varying the effective stroke of the beat-up of the reed. During a succession of partial forward beats (two being a usual number) of the reed, the reed does not carry the picks of weft forward to the fell of the cloth. Then follows 25 a full forward beat of the reed carrying the several picks of weft forward together, and thus piling up the warp threads extending between the group of picks and the fell of the cloth. In order to weave a plain stripe 30 the reed is given its full forward movement at each pick. The "beat-up motion" which thus effects the different forward beats of the lay is well known in several different forms. In some cases the reed is movable 35 on the lay; in others, the stroke of the lay is varied; and in still others the position of the crank shaft forward and back is changed. A typical example is shown in United States Letters Patent of Bardsley 40 No. 937,139, October 19, 1909. The pattern mechanism constituting the present invention controls the beat-up motion and thereby determines the character of the weave whether plain or terry.

45 It is also customary in terry looms to have a positive let-off which acts at each full forward beat of the reed during the terry weave but not otherwise. A typical example is shown in United States Letters Patent of Crowley No. 785,895, March 21, 1905. The present pattern mechanism acts to suspend 50 the positive let-off during plain weaving.

Also, the cloth and warp have been let back in changing between plain and terry weaving to avoid slackness in the fabric at 55

those points, and at intervals during the plain weaving to insure compactness in the fabric. Mechanism for this purpose is disclosed in an application for Letters Patent of the United States of Charles F. Merrill, 30 Serial Number 250,043, filed August 15, 1918. The present pattern mechanism controls the let-back.

The present improved pattern mechanism is illustrated in the accompanying drawings, 65 in which—

Figure 1, is a side view of the pattern mechanism. Fig. 2, is a front view. Fig. 3, is a plan view. Fig. 4, is a horizontal section in the plane indicated by the line 4—4 70 in Fig. 1. Fig. 5, is a vertical section in the plane indicated by the line 5—5 in Fig. 1. Fig. 6, is a vertical section in the plane indicated by the line 6—6 in Fig. 2. Fig. 7, is a vertical section of the rear of the loom 75 illustrating the let-off. Fig. 8, is a detail vertical section in the plane indicated by the line 8—8 in Fig. 7.

The improved pattern mechanism controls the beat-up motion, the let-back and the let-off through two actuators 10, and 11, (Figs. 2, 3, and 5) each shown as a lever pivoted at its outer end.

A wire 12, leads from the inner end of the forward actuator 10, to the let-back motion which may be identical with that set forth in the aforesaid application of Charles F. Merrill. The let-back motion itself constitutes no part of the present invention. It suffices to know that whenever the let-back 90 actuator 10, is lifted its motion is transmitted through the wire 12, and the cloth and warp are let-back. As soon as the actuator 10, drops, the let-back action ceases. The wire 12, is thus a symbol or representative 95 of the let-back motion, and constitutes an operative connection thereto.

A wire 13, leads from the inner end of the rear or terry actuator 11, to the beat-up motion. The beat-up motion itself constitutes 100 no part of the present invention. It may be identical with that set forth in the aforesaid Bardsley patent or in the aforesaid Merrill application. It suffices now to know that when the terry actuator is down, the 105 terry weave continues; and, when said actuator is raised plain weaving is done. The wire 13, thus serves as a representative of the beat-up motion, and constitutes an operative connection thereto.

A second wire 14, leads from the inner end of the terry actuator to the let-off which is shown in Fig. 7. The terry warp 15, runs from the usual terry warp beam (not shown) under idle roll 16, thence around rough surfaced let-off roll 17, thence over and under idle roll 18, and thence to the harnesses. Fast with the roll 17, is a ratchet wheel 19, acted upon by a spring pressed pawl 20. This pawl is pivotally connected to the upper end of a reciprocating rod 21, the lower end of which is adjustably connected to a crank arm 22, fast on a rock-shaft 23. A second arm 24, fast on the shaft 23, has a cam roll 25, traveling in the cam groove of a cam 26, fast on the back-shaft 27, of the loom. As the shaft 27, rotates, the pawl 20, feeds the let-off roll 17, positively forward. The back-shaft 27, is geared to the cam shaft of the loom so as to rotate continuously, and at such a relative speed and timing that the let-off roll is rotated positively at each full forward beat of the reed, thus feeding the warp as the piles are formed. In this respect the action is like that of the aforesaid Crowley patent.

The wire 14, from the pattern controlled terry actuator 11, is connected at its lower end with one arm 28, of a bell crank lever, the other arm 29, of which is connected by a link 30, with the pawl 20. When the terry actuator is lifted, as indicated in Fig. 7, the pawl 20, is swung forwardly out of reach of the ratchet 19, so that the reciprocation of the pawl by the cam 26 is idle. This is the condition during plain weaving. The link 30, permits the idle rise and fall of the pawl. During the terry weave, the terry actuator is down, and the pawl 20, acts upon the ratchet at each rotation of the back shaft.

Fig. 7, shows at 31, the ground warp beam, from which the ground warp 32, runs over the whip roll 33, to the harnesses.

The movements of the two actuators 10, and 11, thus determine the character of the weave, and the action of the let-off and let-back; and are controlled by the illustrated pattern mechanism.

The pattern mechanism is driven from the crank shaft 34, (Figs. 1, 2 and 4) of the loom. At its outer end at one side of the loom the crank shaft has a bevel gear 35, meshing with a bevel gear 36, on a short shaft 37, which at its other end (Fig. 1) has a worm 38. This worm engages a worm wheel 39, on a short shaft 40, which also has a spur gear 41, meshing with a pinion 42, on a third short shaft 43. This shaft 43, has a detachable cam 44 (Figs. 1 and 4) which acts upon the toe 45, of a pawl lever 46, pivoted at 47. A spring 48, maintains the lever toe 45, in contact with the cam 44. Thus the pawl lever 46, is oscillated automatically at a rate dependent upon the gear relation between the shafts 34, and 43, which

can be regulated in accordance with the effect desired. With the illustrated gearing, the pawl lever is oscillated back and forth once for twenty-seven rotations of the crank shaft.

To the upper end 49, of the pawl lever is pivoted at 50, a gravity pulling hooked pawl 51, which rests upon a ratchet wheel 52. The ratchet wheel, as shown in Fig. 5, is detachably secured to a hub 53, which turns 75 on a fixed stud 54. The hub 53, has the pattern cam wheel 55. The pattern cam wheel is advanced a step at each oscillation of the pawl lever, and a towel is woven for each of its revolutions. In the illustrated 80 embodiment, the ratchet wheel has sixty-four teeth; so that a towel would be produced having one thousand seven hundred and twenty-eight picks of weft. This is representative only. A different relation of 85 gears, a cam differing in throw from that of the cam 44, and a ratchet wheel 52, with a different number of teeth, can be employed. All of these elements are readily detachable, so that elements of a similar and modified 90 character can be substituted.

The pattern cam wheel carries two sets of detachable and adjustable cams for the two actuators 10 and 11. As shown, there is one set of four cams 56, 57, 58, and 59, 95 coöperating with the terry actuator 11; and a single block 60, having another set of cams 61, coöperating with the let-back transmitter 10. Each cam 56, 57, 58, and 59, is circumferentially adjustable on the wheel 55, 100 by means of a slot 62, (Figs. 5 and 6) in the cam wheel, and a headed screw 63, extending through the slot and tapping into the cam. The block 60, is circumferentially adjustable by means of the two slots 64, and 105 the headed screws 65. As shown in Fig. 3, the two intermediate cams 57 and 58 overlap each other longitudinally, thereby forming parts of a longitudinally extensible cam. The terry actuator 11, has a depending foot 110 66, coöperating with the set of cams 56, 57, 58, and 59. The cam wheel 55, rotates in the direction of the arrow (Fig. 6), and the meeting faces of the foot and cams are beveled to facilitate the riding of the foot 115 onto the cams.

During the rotation of the cam wheel 52, after the cam 59, has passed the terry actuator and until the cam 56, is reached, the terry actuator is down, terry weaving is 120 done, and the positive let-off is in action. When the cam 56, reaches the foot 66, of the terry actuator, that actuator is lifted, thus establishing plain weaving and suppressing the positive action of the let-off. 125 Plain weaving continues until cam 56, passes the foot 66. Thereupon actuator 11, drops, and terry weaving and the positive action of the let-off are resumed. This condition remains until the cam 57, reaches the foot 130

66, whereupon the actuator 11, is lifted, plain weaving is done and the let-off is no longer positive. These conditions continue until both cams 57, and 58, pass beyond the 5 foot 66, and the actuator 11, again drops. Thereupon terry weaving with the positive action of the let-off is resumed until the cam 59, reaches the foot 66, and lifts the actuator. Plain weaving with no positive 10 action of the let-off then continues until the cycle of rotation of the cam wheel 52 is completed. With the specific arrangement of cams illustrated, a fabric is produced consisting of repetitions of a long body of terry 15 weave, followed by short stripes of plain and terry weave, then a long band of plain weave, and finally short stripes of terry and plain weave. Towels are made from the fabric by cutting across through the 20 middle of the long bands of plain weave (due to the cams 57, and 58); and, each towel has a terry body with a narrow stripe of plain weave and a narrow stripe of terry weave near each end, and at each end a 25 stripe of plain weave.

The cams 56, and 59, are circumferentially adjustable so as to vary the length of the terry body of the fabric. The longitudinally extensible cam, constituted by the 30 two overlapping parts 57, and 58, can be adjusted so as to vary the length of the long band of plain weave and the width of the narrow stripes of terry weave. The several cams 56 to 59, are readily detachable, and 35 can be replaced by different cams, so as to still further vary the character of the weave.

The let-back actuator 10, has a beveled foot 67, (Fig. 6) coöperating with the cams 40 61. When one of the cams 61, passes the foot 67, the actuator 10, rises and immediately falls, thus letting back the cloth and warp one step only and immediately resuming the normal action of the take-up. This 45 is due to the circumstance that the cams 61, are so related to the teeth of the ratchet 52, that the foot 67, never dwells at the top of a cam but only at its bottom. Accordingly, the foot 67, dwells for a long interval at 50 the bottom of one of the cams, and each cam is moved rapidly beneath and past the foot by the spring effected working stroke of the pawl lever. In this connection, it will be noted that the feed of the cam wheel is effected by the spring 48, which imparts the 55 working stroke to the pawl lever. The cam 44, slowly gives the idle return stroke to the pawl lever and compresses the spring. The cams 56 to 59 have a lead over the cams 61, 60 so as to compensate for the position of the actuator 11, ahead of the actuator 10, with respect to the rotation of the cam wheel. With the specific cam relation shown, the let-back action takes place as the change 65 is made between terry and plain weaving,

and also at every advance step of the ratchet wheel during the plain weave. The block carrying the cams 61, is readily detachable, so that a proper block can be used and adjusted in place for each different arrangement of the cams 56 to 59. 70

When the main body of the cam wheel is below the feet 66, and 67, the actuator 11, and 10, rest upon the fixed shouldered stop 68. 75

The hub 53, with the cam wheel 55, and ratchet wheel 52, are removable from the stud. The outer end of the stud is screw threaded to receive nuts 69, 70. By removing these nuts, the hub 53, can be taken off. 80 This facilitates changing cams and ratchet wheels.

To prevent the ratchet wheel 52, and cam wheel 55, overrunning under the impulse of the pawl 51, friction pads (of felt, preferably) 71, are interposed between the ends of the hub 53, and disks 72, slipped upon the stud 54, as shown in Fig. 5. 85

A pivoted gravity' detent 74, prevents backward turning of the ratchet wheel 52. 90 A fixed pin 75, limits the outward swing of the detent.

I claim—

1. A terry loom having a terry actuator operatively connected to the beat-up motion and the let-off, and a let-back actuator operatively connected to the let-back, in combination with a pattern mechanism controlling the movement of said actuator and comprising a cam wheel, two sets of cams 95 adjustably and detachably mounted on said wheel, one set of cams coöperating with the terry actuator comprising a longitudinally extensible cam consisting of two overlapping parts and the set also including other cams 100 separated from each other and the extensible cam, and the other set of cams coöperating with the let-back actuator and all carried by a single block, said cams acting upon the let-back actuator when the terry actuator 105 is both raised and lowered and also at intervals when the terry actuator remains lifted, a ratchet wheel connected with the cam wheel, a pawl lever acting upon the ratchet wheel to move it step-by-step after a succession of beats of the lay, a spring which gives the pawl lever its working stroke, a cam which moves the pawl lever in opposition to the spring, and friction pads acting upon the ratchet wheel to prevent overrunning. 110

2. A terry loom having a terry actuator operatively connected to the beat-up motion and the let-off, and a let-back actuator operatively connected to the let-back, in 125 combination with a pattern mechanism controlling the movement of said actuators and comprising a cam wheel, two sets of cams adjustably and detachably mounted on said wheel, one set of cams coöperating 130

with the terry actuator comprising a longitudinally extensible cam consisting of two overlapping parts and the set also including other cams separated from 5 each other and the extensible cam, and the other set of cams coöperating with the let-back actuator and all carried by a single block, said cams acting upon the let-back actuator when the terry actuator is both 10 raised and lowered and also at intervals when the terry actuator remains lifted, a ratchet wheel connected with the cam wheel, a pawl lever acting upon the ratchet wheel to move it step-by-step after a succession of 15 beats of the lay, a spring which gives the pawl lever its working stroke, and a cam which moves the pawl lever in opposition to the spring.

3. A terry loom having a terry actuator 20 operatively connected to the beat-up motion and the let-off, and a let-back actuator operatively connected to the let-back, in combination with a pattern mechanism controlling the movement of said actuators and comprising a cam wheel, two sets of cams adjustably and detachably mounted on said wheel, one set of cams coöperating with the terry actuator comprising a longitudinally extensible cam consisting of two overlap- 25 ping parts and the set also including other cams separated from each other and the extensible cam, and the other set of cams co-operating with the let-back actuator and all carried by a single block, said cams acting upon the let-back actuator when the terry actuator is both raised and lowered and also 30 at intervals when the terry actuator remains lifted, a ratchet wheel connected with the cam wheel, and a pawl acting upon the ratchet wheel to move it step-by-step after a succession of beats of the lay.

4. A terry loom having a terry actuator and let-back actuator operatively connected to the let-back, in combination with a pattern mechanism controlling the movement 45 of said actuators and comprising a cam wheel, two sets of cams adjustably and detachably mounted on said wheel, one set of cams coöperating with the terry actuator comprising a longitudinally extensible cam consisting of two overlapping parts and the set also including other cams separated from each other and the extensible cam, and the other set of cams coöperating with the let-back actuator and acting upon the let-back actuator when the terry actuator is both raised and lowered and also at intervals when the terry actuator remains lifted, a ratchet wheel connected with the cam 50 wheel, and a pawl acting upon the ratchet wheel to move it step-by-step after a succession of beats of the lay.

5. A terry loom having a terry actuator, and a let-back actuator operatively connect- 60 ed to the let-back, in combination with a

pattern mechanism controlling the movement of said actuators and comprising a cam wheel, two sets of cams adjustably and detachably mounted on said wheel, one set of cams coöperating with the terry actuator 70 and the other set of cams coöperating with the let-back actuator, a ratchet wheel connected with the cam wheel, and a pawl acting upon the ratchet wheel to move it step-by-step after a succession of beats of the lay. 75

6. A terry loom having a terry actuator, and a let-back actuator, in combination with a pattern mechanism controlling the movement of said actuators and comprising a cam wheel, and two sets of cams adjustably 80 mounted on said wheel, one set of cams co-operating with the terry actuator and the other set of cams coöperating with the let-back actuator.

7. A terry loom having a terry actuator 85 and a let-back actuator, in combination with a pattern mechanism controlling the movement of said actuators and comprising a cam wheel, and two sets of cams on said wheel, one set coöperating with the terry actuator 90 and the other set coöperating with the let-back actuator.

8. A terry loom having a terry actuator, in combination with a pattern mechanism 95 controlling the movement of said actuator and comprising a cam wheel, and a set of cams adjustably and detachably mounted on said wheel and comprising a longitudinally extensible cam consisting of two overlapping parts and other cams separated 100 from each other and the extensible cam.

9. A terry loom having a terry actuator in combination with a pattern mechanism controlling the movement of said actuator and comprising a cam wheel, and a set of 105 cams adjustably mounted on said wheel including a longitudinally extensible cam consisting of two overlapping parts.

10. A terry loom having a let-back actuator operatively connected to the let-back, in combination with a pattern mechanism controlling the movement of said actuator and comprising a cam wheel having a set of cams coöperating with the let-back actuator and all carried by a single block, a ratchet wheel 110 connected with the cam lever, a pawl lever acting upon the ratchet wheel to move it step-by-step after a succession of beats of the lay, a spring which gives the pawl lever its working stroke, and a cam which moves the pawl lever in opposition to the spring. 115

11. A terry loom having a let-back actuator operatively connected to the let-back, in combination with a pattern mechanism controlling the movement of said actuator and comprising a cam wheel having a set of 120 cams coöperating with the let-back actuator, a pawl lever acting upon the ratchet wheel to move it step-by-step after a succession of beats of the lay, a spring which gives the 125 pawl lever its working stroke, and a cam which moves the pawl lever in opposition to the spring. 130

pawl lever its working stroke, and a cam which moves the pawl lever in opposition to the spring.

12. A terry loom having a let-back actuator, in combination with a pattern mechanism controlling the movement of said actuator and comprising a cam wheel having a set of cams coöperating with the let-back actuator.
13. A terry loom having a positively acting let-off, a machine driven pawl actuating the let-off during the formation of the terry pile, a lever, and a link connecting said lever and pawl, in combination with pattern controlled mechanism which automatically
- 15

swings said lever to disconnect the pawl from the let-off thereby suspending the positive action of the let-off during the plain weave.

14. A terry loom having a positively acting let-off, and a machine driven pawl actuating the let-off during the formation of the terry pile, in combination with pattern controlled mechanism which automatically disconnects the pawl from the let-off thereby suspending the positive action of the let-off during the plain weave.

In witness whereof I have hereunto signed my name.

ALONZO E. RHOADES.
